CABLE CLAMP

Application filed August 7, 1931. Serial No. 555,794.

The present invention relates to cable clamps, and more particularly to means for tightening and loosening the nuts thereof.

The invention may have other uses, however. Although it is herein shown and described as embodied in a cable clamp of the U-bolt type, it will be apparent that its novel principles may be used, without material change in form, in other types of clamps, or 10 in fact in many other devices in which the tightening or loosening of one or more nuts is an essential factor. It is to be understood, therefore, that the drawing and description herein are by way of example of one concrete 15 form of the invention, and that such form may be varied considerably without departing from the essential principles of the invention as set forth in the claims hereto appended.

20 The general objects of the invention are to provide convenient and rapid means for turning a nut, or two or more nuts simultaneously, and to provide a measure of protection against unauthorized turning thereof. When the invention is embodied in a 25 cable clamp as herein shown and described, the ability to tighten both nuts simultaneously with one hand effects a great saving in time and effort; promotes the safety of the opera-

30 tor and others working with him, especially when working in an awkward position above the ground; prevents bending of the U-bolt due to alternate tightening of its nuts; and eliminates the necessity for making the bolt 35 holes in the body materially larger than the bolt. The ease and speed of operation also permits clamps of this type to be used in many other situations, such as joining together reinforcing bars in concrete work, 40 for which the usual cable clamps are unsuitable because of the time necessarily consumed in tightening them.

The device may be so constructed that its 45 nuts can be turned only by the novel wrench which forms a part of the invention. By limiting possession of such wrenches to certain workmen, unauthorized or careless loosening of a clamp is to a large degree prevented. This is of great advantage in cable rigging work, in which the loosening of one

clamp may endanger the stability of an entire structure.

The above and other objects and advantages of the invention will become more apparent from the following specification and 55 by reference to the accompanying drawings, in which

Fig. 1 is a central section of a cable clamp embodying one form of the invention, showing the wrench in operative position. 60

Fig. 2 is a section on the line 2—2 of Fig. 1.

Fig. 3 is a fragmentary view showing a modified form of nut adapted for engagement both by the novel form of wrench shown in Fig. 1 and by a wrench of ordinary form. 65

In the drawings, the reference numeral 5 designates the body of a cable clamp, and 6 is the U-bolt extending through holes 7 in said body. The cable or cables, not shown, are clamped between the U-bolt and the seat 70 8 in the body in the usual manner. The U-bolt has threaded ends upon which are screwed nuts 9 adapted to bear against the outer face of the body. The nuts are formed with gear teeth 10 upon their peripheral surfaces, which mesh with a gear portion 11 formed upon the shank 12 of a wrench. The latter is preferably, but not necessarily, of T shape, with a handle 13. 75

Means are provided for holding the wrench in proper position with respect to the body 5, so that when turned, its gear portion 11 will mesh with and turn both nuts 9 simultaneously. This preferably comprises a stem or pin 14 extending from the end of the 80 wrench shank 12 and rotatably fitting within a hole or socket 15 in the body, centrally located between the bolt holes 7. The pin 14 preferably projects a sufficient distance beyond the end of the shank 12 to enable it 85 to enter its socket 15 before the gear teeth 10 and 11 engage each other, so that proper engagement of said teeth is easily effected. A pin of such length, however, would extend all the way through the body 5, and strike 90 against the cable, not shown, resting against the seat 8. Therefore the pin 14 is best made retractable within the shank 12, as shown, being held therein by a head 16 and a spring 95 17 confined between said head and the trans-

verse handle 13. Thus before the wrench is brought into operative engagement with the body, the pin 14 projects sufficiently to enable its end to enter the socket 15 and locate the wrench in advance of engagement between the gear teeth 10 and 11, but when the end of said pin strikes against the cable (not shown), it retracts, allowing the wrench to be fully seated. If desired, a locking device, such as 10 a groove 18 in the end of the pin 14 and a ball latch 19 in the body 5, may be provided to hold the wrench in operative position. The ball is yieldably pressed into engagement with the groove 18 by a spring 20.

15 The toothed portions 10 and 11 of the nuts and wrench are preferably made slightly conical, as shown, to facilitate initial engagement. The bases of the nuts 9 are also best formed slightly convex, as shown at 21, to fit 20 dished countersunk seats surrounding the bolt holes 7, in order to center the legs of the U-bolt and prevent them from binding against the sides of its holes.

25 A guard wall or flange 22 is preferably formed upon the body 5 closely surrounding the nuts 9 and the wrench gear portion 11 when the latter is in operative position. This prevents access to the nuts 9 by any ordinary wrench or pliers, and prevents them 30 from being turned except by the gear wrench especially provided. If desired, the pitch or form of the nut teeth or the distance between them can be different in different clamps or series of clamps, so that a wrench 35 provided for one cannot be used for others.

40 When the feature of guarding against unauthorized use is not desired, the nuts can be made as shown in Fig. 3, with a squared or other suitably shaped portion 23 formed above the teeth 10 and adapted for engagement with an ordinary wrench (not shown). In this case the guard wall 22 merely protects the hands of the workman from being 45 caught in the gear teeth when the gear wrench is used, as well as protecting the teeth themselves from injury.

50 It will be seen that after the clamp has been assembled upon a cable and the nuts started upon the ends of the U-bolt, said nuts can 55 be screwed up tight rapidly, with one hand, merely by inserting the wrench and turning it. Both nuts are turned simultaneously, so that there is no unequal drawing up of the two legs of the U-bolt, and no bending thereof. Moreover, the wrench cannot slip off, and even if the workman's hand slips, the wrench will not drop. It will also be seen 60 that the same wrench can be used upon different sizes of clamps, for in larger clamps, with greater distance between legs of the U-bolt, the nuts can, and naturally would, be made of larger diameter, so that the distance between their peripheries would be the same. The pitch and shape of the gear teeth, 65 of course, must correspond to those of the

wrench. However, when it is desired that a certain clamp or series of clamps can be operated only with one wrench, to prevent unauthorized operation, the pitch or shape of the teeth of the nuts, or the distance between them, can be made to fit that particular wrench and no other.

70 It will also be apparent that the invention may be applied to other forms of clamps, and to other devices in which the rapid and convenient turning of one or more nuts is a desired object, the essential feature being the provision of a nut or nuts with gear teeth formed upon their outer or peripheral surfaces, and a wrench having a gear portion adapted to mesh with said nut or nuts, said wrench being operatively and removably associated with the body of the device to insure its proper engagement.

75 We claim:—

1. A cable clamp comprising a body; a U-bolt having its ends extending through said body; nuts threaded upon the ends of said U-bolt, said nuts having gear teeth upon their outer surfaces; and a removable wrench having a gear portion adapted for simultaneous engagement with both said nuts.

80 2. A cable clamp comprising a body; a U-bolt having its ends extending through said body; nuts threaded upon the ends of said U-bolt, said nuts having gear teeth upon their outer surfaces; and a wrench adapted for removable rotative engagement with said body, said wrench having a gear portion 85 engaging both said nuts.

90 3. A cable clamp comprising a body having a pair of spaced holes and a socket between them; a U-bolt extending through said holes; nuts threaded upon said U-bolt, said nuts having gear teeth upon their outer surfaces; and a wrench having a portion adapted for removable engagement with said socket and a gear portion adapted for engagement with said nuts.

95 4. A cable clamp comprising a body having three holes extending therethrough; a U-bolt, extending through the outermost holes; nuts threaded upon said U-bolt, said nuts having gear teeth upon their outer surfaces; a wrench having a gear portion 100 adapted for engagement with said nuts; and a longitudinally retractable guide pin mounted in said wrench and adapted to enter the third hole in said body.

110 5. A cable clamp comprising a body; a U-bolt having its ends extending through said body; nuts threaded upon the ends of said U-bolt; and a removable wrench adapted for simultaneous operative engagement with both said nuts.

115 6. In combination with a body member and a bolt extending therethrough, a nut threaded upon said bolt, said nut having gear teeth formed upon its outer surface; and a wrench removably associated with said 120

130

body member, said wrench having a gear portion adapted for engagement with said nut.

7. In combination with a body member having a bolt hole and an adjacent guide, a bolt extending through said hole; a nut threaded upon said bolt, said nut having gear teeth formed upon its outer surface; and a wrench adapted for removable rotative engagement with said guide, said wrench having a gear portion adapted for engagement with said nut.

8. In combination with a body member and a bolt extending therethrough; a nut threaded upon said bolt, said nut having gear teeth formed upon its outer surface; a wrench removably associated with said body member, said wrench having a gear portion adapted for engagement with said nut; and a guard wall extending from said body member surrounding said nut and the gear portion of said wrench.

9. In combination with a body member and a bolt extending therethrough, a nut threaded upon said bolt, said nut having a portion of its outer surface formed with gear teeth and a second polygonal wrench receiving portion; and a wrench adapted for removable engagement with said body member, said wrench having a gear portion adapted for engagement with the gear portion of said nut.

In testimony whereof we have signed our names to this specification.

CHARLES E. WILKINS.
ARTHUR W. RAFFERTY.
